CLAIM

The ornamental design for a sofa as shown and described.

DESCRIPTION

FIG. 1 is a perspective view of a sofa according to a first embodiment of the design.

FIG. 2 is a front view of the sofa of FIG. 1.

FIG. 3 is a rear view of the sofa of FIG. 1.

FIG. 4 is a first side view of the sofa of FIG. 1.

FIG. 5 is a second side view of the sofa of FIG. 1.

FIG. 6 is a top view of the sofa of FIG. 1.

FIG. 7 is a perspective of a sofa according to a second embodiment of the design.

FIG. 8 is a front view of the sofa of FIG. 7.

FIG. 9 is a rear view of the sofa of FIG. 7.

FIG. 10 is a first side view of the sofa of FIG. 7.

FIG. 11 is a second side view of the sofa of FIG. 7; and,
FIG. 12 is a top view of the sofa of FIG. 7.

Portions of the sofa shown in broken lines are included for the purpose of illustrating environment and form no part of the claimed design.
